9 Claims. (Cl. 73—147)

ABSTRACT OF THE DISCLOSURE

A blow-down type wind tunnel having an arc chamber, nozzle, and evacuated test region is described. An improved liner for the arc chamber is provided having two semi-cylindrical metal halves forming a hollow cylinder for confining an electrical arc for gas heating. Metal electrodes are employed for introducing a heavy current of electricity into the chamber for the arc. The semi-cylindrical halves of the arc chamber are electrically insulated from each other, and from the electrodes which enter from the sides thereof, so that the arc chamber liner is electrically isolated from any possible conduction to ground. In addition, the insulation between the two segments substantially reduces induced currents in the liner during the arc and enhances gas heating efficiency in the wind tunnel.

Certain types of wind tunnels which operate over short time intervals employ an electric arc between two electrodes in an arc chamber to generate a high pressure, high temperature gas from a relatively lower pressure of lower temperature gas in a minimum time interval with little heat loss. The gas then expands into an evacuated chamber at high velocity. These tunnels are known as the blow-down type. It has been found in operation of such wind tunnels that the arc chamber is preferably constructed of metal having a relatively high thermal conductivity so that the large amount of heat dissipated in the arc chamber by the arc is conducted away from the surface to minimize damage to the arc chamber. Arc chamber linings of non-metallic materials have in general been unsatisfactory. Difficulty is also encountered with one piece metallic arc chamber linings due to erosion of the arc chamber lining by the electric arc with consequent contamination of the gas generated thereby. Such added linings have comprised continuous sleeves of metal grounded to the arc chamber housing. There is also found with such arc chamber linings that erratic results are sometimes obtained due to unexplained variations in arc conditions.

It is hypothesized that in the prior art arc chambers an arc has formed between one electrode and the interior of the arc chamber. Current is then conducted through the arc chamber wall to the other electrode and a second arc forms between the wall and the second electrode. Thus there are two relatively low resistance, low power arcs instead of a single relatively higher resistance, higher power arc directly between the electrodes.

It is therefore a broad object of this invention to provide an improved arc chamber.

Thus in the practice of this invention according to a preferred embodiment there is provided a wind tunnel comprising an arc chamber housing and a converging-diverging nozzle connected to the housing leading to a vacuum chamber containing low pressure gas or vacuum. A test model or the like provided in the vacuum chamber adjacent the diverging portion of the nozzle is customarily employed in the use of a tunnel. Oppositely disposed electrodes extending into the arc chamber housing are employed for conducting a very high current for a very short period of time from a bank of capacitors to create

2

a high energy arc or spark within the arc chamber housing.

Within the arc chamber housing there is provided a metal liner encompassing the region in which the electric arc occurs. This arc chamber liner in a preferred embodiment is in the form of a right circular cylinder closed at one end and open at the other. The metal cylinder is split into two separate longitudinal segments along a plane extending along the axis of the cylinder. Electrical insulation is provided between the two halves of the cylinder. Electrical insulation is also provided surrounding the arc chamber liner thereby preventing electrical contact with other electrically conducting components of the wind tunnel. A metal closeout plate is provided over the open end of the arc chamber liner and provides an orifice for the converging section of the nozzle. The electrical insulation between the two halves of the arc chamber liner and surrounding the arc chamber liner alter the electrical characteristics of the arc chamber and virtually eliminate lining erosion. The split liner with electrical insulation prevents the formation of undesired arcs to the walls and increases the power levels obtainable from the arc. In addition to increased power and decreased gas contamination, the improved liner unexpectedly provides better velocity characteristics in the wind tunnel in that a substantial time of constant gas velocity is obtained, in contrast to prior art tunnels that have a single peak of velocity with velocity falling off rapidly thereafter.

30 Thus it is a broad object of this invention to provide an improved arc chamber.

It is another object of this invention to provide an improved wind tunnel.

It is a further object of this invention to minimize electric arc erosion.

It is another object of this invention to provide a stable arc.

Other objects and many of the attendant advantages of this invention will be readily appreciated as the same becomes better understood by reference to the following detailed description when considered in connection with the accompanying drawings wherein:

FIG. 1 illustrates an overall view of a wind tunnel incorporating the principles of this invention;

45 FIG. 2 is a longitudinal sectional view of an arc chamber liner incorporating the principles of this invention;

FIG. 3 is a transverse cross-sectional view of the liner of FIG. 2;

50 FIG. 4 is a sectional view of a portion of the liner of FIG. 2;

FIG. 5 presents graphs of wind tunnel velocity as a function of time; and

FIG. 6 illustrates an alternative embodiment of arc chamber lining.

55 Throughout the drawings like numerals refer to like parts.

Previously during operation of wind tunnels of the blow-down type substantial erosion of the interior of the arc chamber occurred due to arc impingement on the walls of the arc chamber. This not only limited the useful life of the arc chamber but also contributed to contamination of the gas flowing through the wind tunnel with material eroded from the arc chamber. The arc chamber liner described herein substantially reduces metallic contamination of the gas flowing through the wind tunnel. It has been hypothesized that one reason for substantial erosion of the arc chamber in the prior art apparatus has been arcing or sparking between the electrodes and the wall of the arc chamber with accompanying conduction of electricity parallel to the arc through the wall of the arc chamber. Contact of the arc on the wall not only causes erosion of the wall but also diverts some of the

energy available in the capacitors from the arc and reduces the gas velocities obtainable. By providing an arc chamber liner split along a plane normal to the electrodes into two electrically insulated segments, the tendency for the arc to jump to the chamber liner has been effectively eliminated since no continuous current carrying path is now available between the two electrodes except through the arc therebetween.

Another benefit of the improved electrically insulated liner is in the phase relations of the current and voltage in the power circuit. Previously it has been found that the current and voltage maxima are somewhat displaced in time from each other so that maximum power efficiency is not obtained. With the improved electrically insulated arc chamber liner the current and voltage are in better phase relation thereby increasing power efficiency. Random variations in phase relation previously occurred thereby making difficult the prediction of arc energy and hence gas velocity. With the improved liner gas velocity is more accurately controlled by the operator since the phase relations in the arc are substantially constant.

In addition to higher and more predictable energy levels available in the wind tunnel with less erosion of the arc chamber liner, it is unexpectedly found that the velocity characteristics of the gas generated are appreciably improved. FIGURE 5a illustrates schematically the velocity of gas obtained as a function of time in a prior art wind tunnel that is similar to the tunnel described herein except that the prior art arc chamber is a continuous metallic structure rather than specially insulated as described herein. During operation of such a prior art tunnel the velocity of gas flow smoothly increased to a maximum and immediately thereafter began to decrease. The total useful operating time of the tunnel for a given operation is about 50 milliseconds. In a tunnel incorporating the principles of this invention a velocity versus time curve similar to that illustrated in FIGURE 5b is obtained. The useful operating time of the tunnel still remains at approximately 50 milliseconds, however the gas velocity increases to a maximum approximately the same as the maximum obtainable in the prior art tunnel and remains substantially constant near that maximum for approximately 20 to 30 milliseconds before decreasing. This period of substantially constant gas velocity vastly improves the operating characteristics of the tunnel since approximately steady state conditions are maintained for several milliseconds and useful measurements can be made during this time period. Such flow conditions have not been obtained in any prior art blowdown wind tunnels. The increased area under the curve of FIG. 5b is a further indication of the improved power efficiency obtained in the improved liner.

FIG. 1 illustrates a wind tunnel of the blow-down type incorporating the principles of this invention. As illustrated in this embodiment there is provided a vacuum chamber 10 supported by suitable stands 11. The vacuum chamber is connected to a test section 12 of the wind tunnel also supported by a suitable stand 11. During use of the tunnel there is conventionally employed a test specimen 9 seen in FIG. 1 through a window 15 in the test section 12 of the wind tunnel. Connected to the test section is a converging-diverging nozzle 13. The nozzle is in turn connected to an arc chamber housing 14. The vacuum chamber 10, test section 12, and nozzle 13 are in fluid communication with each other. During operation of the tunnel high pressure, high temperature gas generated in the arc chamber housing 14 as hereinafter described expands through the nozzle 13, passes through the test section 12, into the vacuum chamber 10.

For ease in operating the wind tunnel the nozzle 13 and arc chamber housing 14 are mounted on a stand 16 that rolls in grooved tracks (not shown) in the floor so that the nozzle can be separated from the test section for ready access to test specimens. In addition the arc chamber housing 14 is mounted on wheels 17 which permit the

arc chamber housing to be rolled away from the nozzle section 13 for access to the interior of the arc chamber housing. In a preferred embodiment the wheels 17 are constructed of electrically insulating material so that a complete electric circuit does not exist between the arc chamber housing 14, the nozzle unit 13 and the stand 16. The interruption of this electric circuit by the insulating wheels 17 in addition to the insulated liner apparently helps increase reproducibility of the arc conditions and hence the operating conditions of the wind tunnel. In an arc chamber employing heavy currents as described herein, large induced currents are encountered. Previously the resistance of the contact between the arc chamber housing and the stand varied in a random manner and the induced current through the nozzle 13 and stand 16 consequently also varied. Thus the circuit not only drew some power from the arc, but more importantly presented a randomly variable inductance that modified current and voltage phase relations in an uncontrolled manner. Insulation in this circuit has helped increase arc power and also power level predictability.

Leading into the arc chamber housing are two heavy current electrodes 18 and 19. For the purposes of exposition these electrodes are referred to as the upper electrode 18 and the lower electrode 19. Other elements of the wind tunnel may be referred to as upper and lower, vertical or horizontal, and the like. However, it should be understood the relative orientation of components of the wind tunnel relative to some external reference is not essential to the practice of this invention. In addition for purposes of exposition the portion of the arc chamber connected to the nozzle may be referred to as the front end and the opposite portion of the arc chamber is referred to as the rear end.

Within the arc chamber housing 14 there is provided an arc chamber liner 21. The arc chamber liner is illustrated in greater detail in FIGURES 2 and 3 in which the housing 14 is shown only in phantom since the construction thereof will be apparent to those skilled in the art and does not comprise a portion of this invention. As illustrated in these figures the arc chamber liner comprises upper and lower shell-like segments 22, each in the form of a longitudinal half of a hollow right circular cylinder closed at the rear end and open at the front end. In a typical embodiment the shell-like segments 22 are copper with a wall thickness of about $\frac{3}{16}$ inch. The two shell-like segments are assembled in facing relation along a horizontal plane so as to form a hollow right circular cylinder open at the front end and closed at the rear end. In the horizontal plane axially bisecting the two shell-like segments 22 there is provided a layer of insulating material 23 extending so as to completely insulate one of the shell-like segments 22 from the other of the shell-like segments 22. It has been found that a layer of class C mica heater plate 0.025 inch thick is satisfactory insulation. The insulating material 23 is preferably adhesively bonded to the copper of at least one of the shell-like segments to provide ease in manipulation and fabrication.

Surrounding the two shell-like segments 22 there is provided a layer of insulating material 24 such as, for example, glass fiber imbedded in a resin such as an epoxy resin. When cured such a material provides a rigid backing for the shell-like segments and maintains them in proper relation despite disassembly and assembly of the arc chamber. It is desirable to provide a slight taper, such as, for example, one degree, on the outside of the insulation 24 so that a tight fit is readily obtained in the arc chamber housing 14. Metal end bolsters 25 are also conveniently employed for fitting the liner into the housing.

Circular apertures 26 are provided in the metal segments 22 at the top and bottom thereof to permit the upper and lower electrodes 18 and 19 respectively (FIG. 1) to enter the arc chamber liner 21. The axes of the aper-

tures 26 are aligned and normal to the plane formed by the insulation 23. A third somewhat smaller aperture 27 is provided through the junction of the two shell-like segments 22 in the plane of the insulation 23 to permit another electrode to enter the arc chamber as described hereinafter. Electrical insulation 28 is provided around each of the electrode apertures so that the shell-like segments are insulated from the electrodes. There are also provided apertures 29 in each of the shell-like segments 22 which are conveniently used for addition of gas to the arc chamber and for a pressure measuring sensor (not shown). It will be apparent to one skilled in the art that if it is desired to bring electrodes into the arc chamber liner through the ends thereof, apertures would be provided on the ends and the liner would be split laterally by a layer of insulation to perform in a manner similar to the chamber illustrated in the preferred embodiment.

At the front or open end of the arc chamber liner 21 there is provided a copper closeout plate 31. This plate is arranged to seat against the electrical insulation 24 so that it is electrically isolated from the shell-like segments 22. A lip 32 is provided overlapping the end of the electrical insulation 24 and a portion of the segments 22 to minimize hot gas erosion of the insulation. A converging nozzle piece 33 is provided in the front closeout plate. This nozzle piece is aligned with the diverging nozzle section 13 (FIG. 1) of the wind tunnel. A thin diaphragm 34 of plastic material such as polyethylene terephthalate, polyethylene or the like is provided in the throat 35 of the nozzle adjacent the nozzle piece 33. This plastic film resists substantial pressures but is designed to rupture and vaporize under the high pressures and temperatures encountered during operation of the arc chamber. The throat 35 of the nozzle is, for example, less than 0.1 inch diameter, therefore a relatively thin plastic film 34 can withstand high pressures.

FIG. 4 illustrates a partial section of the arc chamber liner with electrodes in place. As can be seen in this figure the upper and lower electrodes 18 and 19 respectively pass through the arc chamber liner 21 and face each other within the arc chamber. A third electrode 36 enters the arc chamber liner through the aforementioned aperture 27 located in the plane of the insulation 23 separating the two shell-like segments 22 of the arc chamber liner. The upper and lower electrodes 18 and 19 are electrically connected to the two sides respectively of a large bank of capacitors 37 which is capable of providing a large current (in the order of 500,000 amperes peak) for a short period of time for the purpose of sustaining an electric arc within the arc chamber. The term electric arc is used herein since the discharge is initiated by other than dielectric breakdown of gas between the electrodes. The term electric spark might also be used since the discharge lasts for a short time interval, usually less than 300 microseconds.

A small wire 38 such as, for example, 0.005 to 0.010 inch tungsten wire, is electrically connected between the upper electrode 18 and the side electrode 36 and is preferably bent to approach but not touch the lower electrode 19. The upper electrode 18 is electrically connected to a switch 39 that is electrically connected to one side of a capacitor 41. The other side of the capacitor 41 is connected to the side electrode 36.

In order to operate the wind tunnel incorporating the arc chamber as described, a plastic diaphragm 34 is placed in the throat of the nozzle and the arc chamber 14 assembled to the nozzle section 13. The vacuum chamber 10 is evacuated and a relatively low pressure of gas such as air, nitrogen or argon is added to the arc chamber by way of one of the pressure ports 29. A pressure of less than 1000 p.s.i.a. in the arc chamber is customarily used. When good vacuum conditions have been obtained in the vacuum chamber the capacitors 37 and 41 are charged by conventional power supplies (not shown).

To operate the tunnel the switch 39 is closed, either

manually or by automatic means, thereby permitting the capacitor 41 to discharge through the fine wire 38. The current suddenly flowing through the wire 38 is sufficient to explode the wire thereby creating an electrically conductive vapor within the arc chamber. This electrically conductive material is sufficient to complete the circuit including the upper electrode 18, the capacitors 37 and the lower electrode 19. The large amount of energy stored in the capacitors 37 is discharged into an electric arc between the upper and lower electrodes 18 and 19 respectively. This electric arc serves to ionize and elevate the temperature of gas within the arc chamber to several thousand degrees and consequently increases the pressure of the gas within the arc chamber to tens of thousands of pounds per square inch. The increased pressure ruptures the plastic diaphragm 34 thereby permitting the gas to expand through the nozzle 13 and flow through the test section 12 at high velocity to the vacuum chamber 10. The high temperature and pressure of the gas within the arc chamber results in a substantial volume of gas flowing through the nozzle and the test section of the wind tunnel. A substantial flow is obtained for a period of approximately 50 milliseconds with peak gas velocities of several thousand feet per second.

The provision of a split liner in the arc chamber with electrical insulation between the two halves has increased the life of the arc chamber liner in a blow-down type wind tunnel and substantially reduced contamination of the gas with metal vapor. This result is considered to arise from the insulation between the liner halves which interrupts the prior art circuit through the arc chamber walls, electrically parallel to the arc, which may serve to conduct current and divert the arc from between the electrodes so as to flow through the arc chamber wall. Such diversion of the arc, which has apparently been eliminated in the improved liner, erodes the liner at the point of contact of the arc on the liner and contaminates the gas. Severe pitting was encountered in prior art arc chambers, limiting the useful life thereof. The improved liner operates without pitting.

In addition to the electrical insulation separating the mutually insulated segments of the arc chamber liner there is provided a layer of electrical insulation completely surrounding the metallic arc chamber liner. This electrical insulation isolates the shell-like segments from the remainder of the arc chamber housing and effectively makes both shell-like segments electrically floating. It is hypothesized that during operation of the arc chamber the upper shell-like segment rapidly acquires an electric charge similar to that of the upper electrode due to some electron flow therebetween and the lower shell-like segment acquires an electric charge similar to that of the lower electrode. These similar charges tend to repel the arc, thereby further inhibiting arcing between the electrodes and the arc chamber liner. Because of these advances it has been possible in a typical wind tunnel to increase the spacing between the upper and lower electrodes about one-third thereby substantially increasing the ratio of arc impedance to the intrinsic circuit impedance of the circuit including the capacitors 37. This places a greater proportion of the stored energy of capacitors in the arc than was available before, thereby permitting operation of the wind tunnel at higher energy levels.

Higher energy levels than in prior art arc chambers are consistently obtainable since the insulated arc chamber provides electric arcs with reproducible phase relations between the voltage and current. In the prior arc chamber the arc energy as a function of time went through a series of maxima and minima, thereby degrading the power efficiency. It is found with the improved arc chamber that consistent time intervals are obtained between arc initiation and the current and voltage maxima and a single large peak of arc energy as a function of time is obtained with a few minor small peaks. This not only permits operation at high power levels, but also increases

the reproducibility in preselecting a wind tunnel operating condition.

This result is apparently due to the elimination of extraneous induced currents both in the arc chamber liner and from the arc chamber through the stand 16. In the prior art arc chambers these induced currents contributed to the reactance of the capacitor-electrode circuit thereby shifting the phase relation and degrading power efficiency. The arc circuit is now damped principally by resistance of the arc thereby increasing both power efficiency and reproducibility. The reactance due to the induced currents could not be readily compensated in the prior art arc chambers since the magnitude of the induced current was not constant from one tunnel operation to the next. It is found with the improved electrically insulated liner that the induced currents, if any, are substantially constant and that adjustment of the phase relation of the current and voltage in the power circuit is readily obtained.

FIG. 6 illustrates another embodiment of arc chamber liner incorporating the principles of this invention. As illustrated in this embodiment there are provided a plurality of metal longitudinal segments 42 of a right circular cylinder with each of the segments 42 separated by a layer of insulation 43 from each adjacent segment 42. The cylinder thus formed is surrounded by a layer of insulation 44 which insulates the metallic portion of the liner from other metallic elements of the arc chamber. An arc chamber liner constructed in the manner illustrated in FIG. 6 functions like the arc chamber described hereinabove and further reduces currents induced in the liner to give better power efficiency and lower circuit inductance. It will be apparent that if electrodes are brought through the end of a cylinder, a series of mutually insulated rings can be employed to form an arc chamber liner incorporating the principles of this invention.

Obviously many variations and modifications of the present invention are possible in light of the above teachings. It is therefore to be understood that within the scope of the appended claims the invention may be practiced otherwise than as specifically described.

What is claimed is:

1. In an arc chamber for carrying a heavy current in an electric arc for a period of time substantially less than one second including an arc chamber housing, a first electrode extending within said housing and insulated therefrom, a second electrode extending within said housing and insulated therefrom, and means for providing a large flow of electricity to said first and second electrodes for causing an arc therebetween, an improved arc chamber liner comprising:

first and second metal segments in the form of longitudinal segments of a hollow cylinder cooperating to at least partially define a hollow cylinder including means for introducing the electrodes into the hollow cylinder from the sides thereof; and electrical insulating material separating said first and second segments from each other and from the arc chamber housing.

2. In an arc chamber for carrying a heavy current in an electric arc for a period of time substantially less than one second including an arc chamber housing, a first electrode extending within said housing and insulated therefrom, a second electrode extending within said housing and insulated therefrom, and means for providing a large flow of electricity to said first and second electrodes for causing an arc therebetween, an improved arc chamber liner comprising:

first and second metal segments cooperating to at least partially define a hollow cylinder with a plane separating said first and second metal segments, each of said segments having an electrode receiving aperture normal to the plane separating said first and second metal segments; and

a layer of electrically insulating material in the plane

separating said first and second segments for insulating said first segment from said second segment.

3. An arc chamber liner comprising: first and second metal shell-like segments each in the form of a longitudinal half segment of a hollow right circular cylinder open at one end and closed at the other end, said segments being assembled in facing relation to define a hollow right circular cylinder, each of said segments having an aperture extending transversely completely through a side thereof for receiving an insulated electrode, said apertures being axially aligned with each other and normal to the plane separating said first and second segments; and a layer of electrically insulating material between said first segment and said second segment for insulating said first segment from said second segment.

4. An arc chamber liner as defined in claim 3 further comprising:

a layer of electrically insulating material contiguously surrounding said assembled segments for electrical isolation thereof.

5. In a wind tunnel of the blowdown type including a vacuum chamber, a converging-diverging nozzle connected to said vacuum chamber, and an arc chamber assembly connected to said nozzle, an improved arc chamber assembly comprising:

an arc chamber housing; an erosion resistant liner in said housing comprising a first metal shell-like segment, a second metal shell-like segment cooperating with said first metal shell-like segment to at least partially define a gas containing volume, and means for insulating said second segment from said first segment; oppositely disposed electrodes entering said housing and said liner; and means for insulating said liner from said housing and from said electrodes.

6. In a wind tunnel comprising a vacuum chamber; a converging-diverging nozzle connected to said vacuum chamber; an arc chamber housing connected to said nozzle so that gas can flow from said arc chamber housing through said nozzle to said vacuum chamber; first and second electrodes passing into said arc chamber housing; and a capacitor connected to said first and second electrodes for supplying electric power thereto; the improvement comprising:

an arc chamber liner in said arc chamber housing comprising first and second metal segments assembled in facing relation to at least partially define a gas filled volume, each of said segments having an electrode receiving aperture, said apertures being aligned and normal to a plane separating said first and second segments so that the electrodes are in facing relation within said arc chamber liner;

a layer of electrically insulating material between said first segment and said second segment for insulating said first segment from said second segment; and a layer of electrically insulating material surrounding said assembled first and second segments for electrical isolation thereof.

7. A wind tunnel comprising: a vacuum chamber; a converging-diverging nozzle connected to said vacuum chamber; an arc chamber housing connected to said nozzle so that gas can flow from said arc chamber housing through said nozzle to said vacuum chamber;

a support means for supporting said arc chamber housing; electrical insulating means for at least partially insulating said arc chamber housing from said support means;

a liner in said arc chamber housing defining a gas containing volume, said liner comprising first and second metal segments cooperating to define a right circular

cylinder, and electrical insulation separating said first and second segments; electrical insulation between said liner and said arc chamber housing; first and second electrodes passing through said arc chamber housing into the gas containing volume; and a capacitor connected to said first and second electrodes for supplying electric power thereto.

8. A wind tunnel comprising:

10 a vacuum chamber;

a converging-diverging nozzle connected to said vacuum chamber;

15 an arc chamber housing connected to said nozzle so that gas can flow from said arc chamber housing through said nozzle to said vacuum chamber;

a support means for supporting said arc chamber housing;

20 electrical insulating means for at least partially insulating said arc chamber housing from said support means;

25 an arc chamber liner in said arc chamber housing comprising first and second metal shell-like segments each in the form of a longitudinal half segment of a hollow right circular cylinder open at one end and closed at the other end, said segments being assembled in facing relation to define a hollow right circular cylinder, each of said segments having an aperture through a side thereof, said apertures being aligned and normal to the plane separating said first and second segments;

30 a layer of electrically insulating material between said first segment and said second segment for insulating said first segment from said second segment;

35 a layer of electrically insulating material surrounding said assembled first and second segments for electrical isolation thereof;

first and second electrodes passing through the apertures in said arc chamber liner; and

40 a capacitor connected to said first and second electrodes for supplying electric power thereto.

9. A wind tunnel comprising:

a vacuum chamber;

a test section connected to said vacuum chamber;

45 a converging-diverging nozzle connected to said test section;

an arc chamber housing connected to said nozzle so that gas can flow from said arc chamber housing through said nozzle and said test section to said vacuum tank; a rupturable diaphragm in the throat of said nozzle; a support stand for said arc chamber housing; electrical insulation between at least a portion of said arc chamber housing and said support stand;

an arc chamber liner in said arc chamber housing comprising first and second metal shell-like segments each in the form of a longitudinal half segment of a hollow right circular cylinder open at one end and closed at the other end, said segments being assembled in facing relation to define a hollow right circular cylinder, each of said segments having an aperture in a side thereof, said apertures being aligned and normal to the plane separating said first and second segments, each of said segments having a recess in an edge thereof forming an aperture in the assembled segments in the plane separating said first and second segments;

a layer of electrically insulating material between said first segment and said second segment for insulating said first segment from said second segment;

a metal piece in the open end of said arc chamber liner for closing out the right circular cylinder, said metal piece being electrically insulated from said segments;

a layer of electrical insulating material surrounding said assembled first and second segments for insulating said segments from said arc chamber housing;

first and second electrodes passing through the apertures in the sides of said segments of said arc chamber liner so as to be aligned and have the inner ends thereof spaced apart;

a third electrode passing through the aperture formed between the edges of said segments of said arc chamber liner;

a fine conductive wire electrically interconnecting said first electrode with said third electrode inside said arc chamber liner;

a first energy storage capacitor having two sides electrically connected to said first and second electrodes respectively;

a second energy storage capacitor having two sides electrically connected to said first and third electrodes respectively, the energy capacity of said second capacitor being sufficient to vaporize said wire; and

a switch in one of the connections of said second capacitor to said electrodes.
